UNITED STATES PATENT OFFICE

ALBERT S. BIERFIELD, OF CHICAGO, ILLINOIS, ASSIGNOR TO HOME SAFETY CORPORATION, A CORPORATION OF ILLINOIS

WINDOW GUARD

Application filed December 3, 1928. Serial No. 323,233.

My invention relates to window guards or gratings, and more particularly to an adjustable and collapsible guard or grating for window openings consisting of a plurality 5 of removable and adjustable bars extending across the window for preventing passage therethrough when the window sash is open.

The main object of the invention is to provide a barrier or guard of the character described which may be easily and readily installed and locked in operative position in any window frame or easily removed therefrom without the use of any fastening devices other than those provided by the guard 10 itself and an ordinary key or wrench, said guard being adapted for installation in window frames of varying widths.

Another object of the invention is to provide a guard or grating of the character described comprising a plurality of vertically and laterally disposed interlocking rods adapted for installation in window frames of varying widths, and means associated with 15 said laterally disposed rods for adjusting the grating laterally so as to cause the vertically disposed rods to engage in the sash grooves of the window frame and force and lock them securely therein.

A further object of the invention is to provide a device of the character described, which is adapted for ready installation in a window frame of varying widths to form a strong and compact guard or barrier therefor, for preventing passage therethrough, and means associated with said device, for 20 locking the same in operative position said means being operable only by those authorized to operate the same for unlocking the said barrier or guard and removing the same 25 from the window frame.

A still further object of the invention is to provide a guard of the character described comprising a plurality of interengaging rods which when in fully assembled position in the frame of a window form a strong and compact guard therefor, said guard being collapsible when not in use whereby the same may be folded into a neat and compact package which may be easily transported from 30 place to place.

A still further object of the invention is to provide a novel and improved adjustable and collapsible window guard of the character described, which will be simple in construction, easily assembled and locked in 35 place in a window frame, of varying widths, readily removable and collapsed into a small and compact package for transporting the same from place to place, cheaply manufactured, and efficient in carrying out the purposes for which it is designed.

With the foregoing and other objects in view, which will appear as the description proceeds, the invention consists in certain novel and improved features of construction, 40 arrangement, and combination of parts, hereinafter more fully described, illustrated in the accompanying drawings, and particularly pointed out in the appended claims, it being understood that various changes in the 45 form, size and minor details of the structure may be made without departing from the spirit or sacrificing any of the advantages of the invention.

Stated generally, the invention comprises a pair of upright rods adapted to be positioned below the upper sash of a window frame and fitted in the grooves in which the said upper sash slides. The said upright rods are provided in their inner sides with a plurality of 50 equally spaced openings in which are adapted to be received the ends of suitable laterally disposed rods, the free ends of said lateral rods extending to a point near the middle of the window, and mounted upon corresponding free ends of said lateral bars are adjustable sleeves provided with suitable set screws adapted for securely locking said sleeves on 55 said lateral rods. The set screws are only engageable by a suitable key for tightening and loosening the same, thereby preventing the unauthorized unlocking of said sleeves and thereby the removal of said grating. The 60 whole of the above grating may be readily disassembled when not in use and collapsed 65 to form a neat and compact package, which may be easily carried from place to place.

For the purpose of facilitating an understanding of my invention I have illustrated in the accompanying drawings a preferred em- 70

bodiment thereof, from an inspection of which, when considered in connection with the following description, my invention, its mode of construction, assembly, and many of its advantages should be readily understood and appreciated.

Referring to the drawings, in which similar characters of reference are employed to indicate corresponding or similar parts throughout the several figures in the drawings:

Fig. 1, is a side elevational view of the guard in fully assembled and locked position mounted within the frame of a window;

Fig. 2, is a cross sectional view taken on line 2-2 of Fig. 1;

Fig. 3, is a fragmentary view in perspective of the side rods;

Fig. 4, is an enlarged elevational view of one of the sleeves connecting the free ends of a pair of lateral rods; and

Fig. 5, is a view in perspective of the inner ends of the lateral rods.

Referring to the drawings more specifically, the reference character 1, designates a window frame having a lower sash 2, and an upper sash 3. The sides of the window frame, 1, are provided with the usual sash grooves 4, in which the sash 3, is slidably mounted. The grating is adapted to be mounted in the window frame directly beneath the upper sash 3, so as to extend on each side thereof into the grooves 4.

The grating is composed of upright or vertically disposed rods or bars 5, of which there are two, one for each side of the window frame, said rods being of identical construction and size and obviously interchangeable. The rods 5, are adapted to be disposed and fitted within the grooves 4, where it will prevent the lowering of the upper sash 3, but will not interfere in any way with the lowering and raising of the lower sash 2, which may operate in the usual manner. Each of the rods 5, are provided on their inner face with suitable openings or bores 6, equally spaced from each other, and provided with a flattened surface or side 7, for a purpose to be presently described. Lateral or cross rods, 8, are provided, said rods having one of their ends reduced in diameter as shown at 9, which reduced end is adapted to be received in an opening 7, in the side rod 5, one face or side of said reduced end being flattened to correspond to the surface 7, in the opening 6, whereby when said rod 8, is in assembled position, the same will not be rotatable in the opening 6, whereby when said rods 8, are in assembled position, the same will not be rotatable in the openings 6. The rods 8, are of identical construction, shape and size and may, of course, be readily interchanged.

Mounted on the free inner ends of any pair of corresponding lateral or cross rods 8, is a sleeve member 10, said sleeve being adapted

to receive the ends of a corresponding pair of lateral rods, and is slidably adjustable thereon. The sleeves 10, are laterally adjustable with respect to the lateral rods 8, by the telescoping of the free ends of said rods 8, within the sleeve 10, by means of which the grating is adjustable to fit window casings of varying widths.

For securing the grating in its lateral adjustable position, there are provided on each of the sleeves 10, adjacent each end thereof a suitable set or lock screw 11, each of which set screws is provided with a recess or depression 12, in its outer end or head, which recess may be of various shapes, whereby a special key will be required for loosening or tightening the said set screws, consequently, the set screws 11, cannot be loosened by an unauthorized person. The set screws 11, are adapted to extend through the wall of the sleeve 10, and engage the rod 8, for securely locking the sleeve on the rod 8, in the desired adjusted position.

In operation, the grating may be assembled in the window frame as follows: The vertical rods or bars 5, are disposed within the grooves 4, of the window casing, with the openings 6, therein, facing inwardly and towards each other. The cross rods 8, are then fitted into the said openings 6, and the sleeves 10, are then slipped over the inner ends of each pair of corresponding cross rods, and the set screws 11, tightened for securely locking the grating in place, said sleeves being disposed or positioned, so that the set screws therein will face towards the inside of the room, in which the window frame is located, thereby preventing anyone from the outside of the building to operate said screws. The grating is now in its fully assembled and adjusted position in the window casing and is securely locked therein, and when in this position it will be noted that the lower window sash may be lowered and raised at will. To remove the grating, the set screws are loosened, by means of the special key provided therefor, the sleeves are then moved out of engagement with the inner ends of the rods upon which it is mounted, and the rods 8, then disengaged from the side members 5, and removed, after which the side rods 5, may be removed from the grooves 4. The said rods 5, 8, and the sleeves 10, may easily be rolled into and formed into a neat and compact package which may be easily transported from place to place, or packed away into a minimum of space.

From the above it will be noted, that a novel and improved window guard which is adjustable and collapsible is provided, which will positively prevent entrance of an unauthorized person through a window into a building, and that the device may be readily and easily installed or removed by one authorized to do so.

It will also be noted, that the grating con-

sists of a minimum of parts which may be readily interchanged, thus producing a device which may be cheaply and economically manufactured.

5 It is believed that my invention, its mode of construction, and many of its advantages should be readily understood from the foregoing without further description; and should also be manifest that while a preferred embodiment of the invention has been shown and described for illustrative purposes, the structural details are nevertheless capable of wide variation within the purview of my invention, as defined in the appended claims.

10 15 What I claim and desire to secure by Letters Patent of the United States, is:—

1. A window grating comprising a pair of upright rods adapted to be fitted within the vertical grooves of a window casing, said upright rods being provided with a plurality of spaced openings of non-circular cross section on one face thereof, cross rods received within said openings and mounted between said upright rods, sleeves carried by said cross rods for adjusting the said cross rods to the required distance between said upright rods, and means associated with said sleeves for securely locking the said cross rods to said uprights in their desired adjusted position, said means being disposed so as to be operable from the inside of the window casing only.

2. A window grating of the character described, comprising a pair of upright members adapted to be fitted within the vertical grooves of a window casing, said upright members being provided with a plurality of spaced openings of non-circular cross section, cross rods each having one of their ends received within one of said openings of one of said upright members, corresponding cross rods similarly mounted in the other of said upright members, the free ends of any pair of cross rods mounted in the same horizontal plane being spaced from each other, a sleeve for receiving the said free ends of any pair of corresponding cross rods and for spanning the distance therebetween, means associated with said sleeves for securely locking the same to the pair of corresponding cross rods upon which it is mounted, and also for locking said rods to said upright members, said means being operable only from the inside of said window casing.

3. A window grating of the character described, comprising a pair of upright members, a plurality of rods fitted in one of said members, and corresponding cross rods fitted in the other of said members cooperating means formed between said members and cross rods for preventing the rotation of said rods in said members, the free ends of each pair of corresponding cross rods being spaced from each other, said spaces being spanned by sleeves carried by said cross rods, and means associated with said sleeves for se-

curely locking said sleeves to said rods, and a special key for operating said last mentioned means.

4. A window grating of the character described, comprising a pair of upright members, the inner faces of which are provided with a plurality of spaced openings of non-circular cross section, a plurality of cross rods having one of their ends fitted in said openings, and corresponding cross rods having one of their ends fitted in the openings provided in the other of said upright members, the free ends of each pair of corresponding cross rods being disposed within the same horizontal plane and spaced from each other, a sleeve mounted on said free ends and adapted for spanning the distance between said ends, set screws extending through said sleeves adjacent each end thereof for engaging the said cross rods, depressions in the heads of said set screws adapted for engagement by a special key for operating said set screws, and means formed on said rods for preventing the turning of the same when the said device is in fully assembled position.

In testimony thereof, I affix my signature.
ALBERT S. BIERFIELD.
